UNITED STATES PATENT OFFICE

JOHN T. SCULLY, OF NEW YORK, N. Y.

FRICTION LIGHTING DEVICE

Application filed April 3, 1930. Serial No. 441,335.

This invention relates to improvements in friction lighting devices and has especial reference to the portable type of lighter, an object being to provide a lighter which is 5 very compact.

Another object of the invention is the provision of a lighter having a crank which is actuated by a spring lever, or, in a modified form by the cap through the means of a 10 connecting rod.

A still further object of the invention is the provision of a lighter capable of combination with other useful articles, especially a lead pencil, being at the same time graceful in design and easily transformed from a pocket type into a standing type for table 15 or desk use by the mere substitution of a plug for the pencil portion.

With the above and other objects in view, 20 the invention further includes the novel features and details of construction to be hereinafter more fully described, illustrated in the accompanying drawing and pointed out in the appended claims.

25 In the drawing:-

Figure 1 is a front elevation of the invention in combination with a pencil.

Figure 2 is a front view of the invention with part of the cap removed.

30 Figure 3 is a side view of the invention with parts broken away.

Figure 4 is a top view of the invention with parts removed.

Figure 5 is a detail of parts of the 35 invention.

Figure 6 is a detail of modification of a part of the invention.

Figure 7 is a side view with parts broken 40 away of a modification of the invention.

45 Referring to the drawing in detail: Figure 1 illustrates a form of my invention wherein a cap 2 is mounted on the lighter body 1 and, as shown in closed position, covers the spark producing members. Se- 20 cured on the body 1 by a rivet or screw

is a yieldable element 4 one end of which terminates within the cap 2 and which has a lower portion 18 constructed after the manner of the well known pocket clip. Joined to the lower end of the elongated body 1 is 50 a mechanical lead pencil 5, whose upper end within the body 1 serves as a plug. As shown in Figure 3 an end of the elongated body 1 is internally threaded in a cylindri- 55 cally shaped body which is adapted to receive a pencil end, a suitable plug, a pen-knife, nail file or other suitable article.

In Figure 2, I show a front view of the invention, in which the front portion of the cap 2 is removed. The abrading member 8 is carried by a crank 10 mounted in bearings 9 and 9^a, and is movable through an arc by pressure on the yieldable element 4 whose upper end is provided with an elongated slot 16, (Fig. 3), through which the crank 10 passes. The abrader 8 moves through an arc substantially at right angles to the bore of the holder 11 for pyrophoric material 14, and the inner face 8^a of the abrader is roughened or file cut. By pressing inwards with the finger upon the yieldable element 4, the crank 10 is caused to move the abrader 8 through an arc so that the inner face 8^a of the abrader creates 60 friction with the pyrophoric material 14 in the tubular holder 11 which is carried by the support 9^b. A spring, preferably a coil, 13 is held by a screw 12 in the bore of the holder 11, and holds the pyrophoric material 14 in yieldable engagement with the abrader face 8^a. 70

It will be seen, therefore, that movement inwards of the yieldable element 4 will cause a spark wherewith a fuel saturated wick 22 in the holder 15 will become inflamed. The wick holder 15 is positioned in proximity to the spark producing members and leads from the interior chamber of the body 1. The same movement towards the body 1 of the element 4 disengages the catch 6 from the 80 85 90 95

notch 7 on the cap 2, permitting a spring 3 which is held under tension by the cap 2 when the latter is closed to force the cap into open position. It will be observed that in 5 this form should the lighter "fail" or the light be blown out by the wind, it will be unnecessary to close the cap to make a second attempt at a light. The yieldable element 4 will reciprocate to its original position and the device will then be ready for a second attempt.

In a modified form of the invention, as shown in Figure 7, I do not actuate the crank 10 by means of the yieldable element 15 4 which, however, is still employed to hold or release the cap 2 which is hingedly secured to the body 1 as at 17. Instead, I employ an arm link 19 having an end secured to the cap 2, and its opposite end 20 formed with a loop 16^a which engages the crank. As pressure on the yieldable element 4 releases the cap 2 through the catch 6 and notch 7, the yieldable element 23 forces the cap into open position and maintains 25 the cap in this position until the cap is manually closed again where it is normally held under tension by the spring or yieldable element 23. As the cap flies open the arm link 19 which is secured to the cap 30 pulls the abrader member 8' through an arc by means of the crank 10, and the abrader member face 8^a, being in frictional engagement with the pyrophoric material in the holder 11, causes a spark which ignites the 35 fuel saturated wick 22.

The invention is susceptible to many changes in its proportions, form and minor details of construction and the right is 40 herein reserved to make such changes as properly fall within the scope of the appended claims.

Having thus described my invention, I claim:

1. In a friction lighter in combination, an 45 abrader element supported in proximity to a holder for pyrophoric material, said abrader element acting in a plane substantially at right angles to the plane of the bore of said holder for pyrophoric material, a crankshaft connected with said abrader element and having a bent portion disposed 50 between bearings, and means including an elongated aperture engaging the bent portion of said crankshaft to actuate said 55 crankshaft and said abrader element by movement of said means.

2. In a friction lighter in combination, a 60 pivotally mounted abrader element, a holder having a bore therein to hold pyrophoric material, said abrader element acting in a plane substantially at right angles to the plane of the bore of said holder for pyrophoric material and having on its side adjacent the orifice of said bore of said holder 65 an abrading surface, a crankshaft connected

with said abrader element and having a bent portion disposed between bearings, and means including an elongated aperture engaging the bent portion of said crankshaft to actuate said crankshaft and said abrader element by movement of said means.

3. In a friction lighter, the combination of an elongated casing, spark producing members supported by a head of said casing at one end thereof, means to hold a wick in proximity to the spark producing members, said spark producing members including an abrader element acting in a plane substantially at right angles to the plane of the bore of a holder provided with pyrophoric material, a crankshaft connected with the abrader element and having a bent portion disposed between bearings, a cap mounted at one end of said elongated casing to cover and uncover said spark producing members, a yieldable lever element secured to said casing and provided with an elongated aperture to engage the bent portion of and to actuate the crankshaft and also provided with means wherewith to releasably hold said cap in closed position, and means acting on said cap to force said cap open when said cap is released by pressing said yieldable element.

4. A friction lighter including the combination of an elongated casing including a fuel chamber, a wick, means to hold the wick leading from said fuel chamber to a position in proximity to spark producing members, spark producing members supported by the head of said casing at one end thereof, said spark producing members including an abrader element acting in a plane substantially at right angles to the plane of the bore of a holder for pyrophoric material and a holder for said pyrophoric material, a spring held in said bore to hold said pyrophoric material in engagement with said abrader element, a crankshaft connected with the abrader element and having a bent portion disposed between bearings, a cap mounted at one end of said elongated casing to cover and uncover said spark producing members, a yieldable lever element secured to said casing and having a lower yieldable portion to act as a pocket clip and an upper yieldable portion including an elongated aperture providing means to engage the bent portion of and combinedly actuate the crankshaft and notch means adapted to coact with said yieldable upper portion and said cap to releasably hold said cap in closed position, and means acting on said cap to force said cap open when said cap is released by pressing the upper portion of said yieldable lever element.

5. A friction lighter including the combination of an elongated casing including a fuel chamber having means at one end thereof to hold in removable engagement an

elongated handle for at least one tool, a wick leading from said fuel chamber, spark producing members supported by a head of said casing at one end thereof, means to
5 hold an end of the wick in proximity to the spark producing members, said spark producing members including a holder for pyrophoric material and an abrader element acting in a plane substantially at right
10 angles to the plane of the bore of the holder of pyrophoric material, a spring held in said bore to hold said pyrophoric material in engagement with said abrader element, a crankshaft connected with said abrader element
15 and having a bent portion disposed between bearings, a cap including notch-catch means mounted at one end of said elongated casing to cover and uncover said spark producing members, a yieldable lever element
20 having a lower yieldable portion to act as a pocket clip secured to said casing and also including an upper yieldable portion including an elongated aperture to engage the bent portion of said crankshaft, a catch provided upon said upper portion to cooperate with the catch of said cap to releasably hold the cap in closed position, and yieldable means acting upon said cap to force said cap open when said catches are disengaged
25 by pressing the upper lever portion of said yieldable lever element.

In testimony whereof I, JOHN T. SCULLY,
hereunto affix my signature.

JOHN T. SCULLY.
